(57) **CLAIM**

The ornamental design for a portable integrated fire striker with a telescoping bellows, as shown and described.

DESCRIPTION

FIG. 1 is a front elevational view of my design;
FIG. 2 is a top left perspective view of my design;
FIG. 3 is a rear elevational view of my design;
FIG. 4 is a bottom view of my design;
FIG. 5 is a top view of my design;
FIG. 6 is a bottom rear perspective view of my design;
FIG. 7 is a top left perspective view of my design, illustrating the fire striker portion removed with the telescoping bellows in a partially extended position;
FIG. 8 is a bottom rear perspective view of my design of FIG. 7, illustrating the fire striker portion removed with the telescoping bellows in a partially extended position;
FIG. 9 is a front elevational view of my design, illustrating the fire striker portion removed with the telescoping bellows in a fully extended position;
FIG. 10 is a front perspective view of my design, illustrating the fire striker portion removed with the telescoping bellows in a fully extended position;
FIG. 11 is a right side bottom perspective view of my design, illustrating the telescoping bellows in a fully extended position; and,
FIG. 12 is a right side bottom perspective view of my design, illustrating the telescoping bellows in a fully extended position.
